UNITED STATES PATENT OFFICE.

GEORGE HENRY WHEARY, OF RACINE, WISCONSIN.

WARDROBE-HANGER DEVICE.

1,262,605.

Specification of Letters Patent.

Patented Apr. 9, 1918.

Application filed June 8, 1914. Serial No. 843,689.

To all whom it may concern:

Be it known that I, GEORGE H. WHEARY, a citizen of the United States, and resident of Racine, in the county of Racine and State 5 of Wisconsin, have invented new and useful Improvements in Wardrobe - Hanger Devices, of which the following is a description, reference being had to the accompanying drawings, which are a part of this specification.

10 This invention relates to improvements in wardrobe hanger devices.

In dwelling houses or other places of abode the wardrobe closets are usually provided with ordinary clothes hooks which are fastened to the side walls of the rooms. Garments mounted on hangers provided with central hooks are usually supported from the clothes hooks and as the clothes 20 hooks are placed comparatively close together the garments on the hooks necessarily overlap one another and it is impossible to remove some of the garments without first removing the hangers positioned in front of the garments it is desired to remove. A further objectionable feature of the ordinary closet arrangement for supporting clothes is that while the closet is comparatively large with relation to the number 25 of garments usually supported therein, the space is not used to the best advantage and consequently is wasted.

It is one of the objects of the present invention to overcome the before mentioned 30 objectionable feature and provide a wardrobe hanger device which may be secured to one of the side walls or to the inner side of the door of a closet and which is adapted to support, comparatively, a large number 35 of garment hangers in such a manner as to permit the convenient removal of any garment from its hanger without removing any of the other hangers or garments supported thereon.

40 A further object of the invention is to provide a wardrobe hanger device which may be easily removed or replaced in position and which occupies but a minimum amount of space when in use.

45 A further object of the invention is to provide a garment hanger device which is adapted to support garment hangers thereon of the double hook type now in use in wardrobe trunks of the better class whereby 50 garment hangers may be interchangeably

used in a trunk or in connection with the improved hanger device.

A further object of the invention is to provide a wardrobe hanger device in which the garment hanger tracks thereof are provided with extensible ends which while normally in a closed garment holding position may be swung to positions in longitudinal alinement with the hanger tracks to permit garment hangers mounted thereon to be 60 moved outwardly upon the extensible ends 65 to positions of easy accessibility.

A further object of the invention is to provide a wardrobe hanger device which is of simple construction, is strong and durable and is well adapted for the purpose described.

With the above and other object in view, the invention consists of the improved wardrobe hanger device and its parts and combinations as set forth in the claims, and all equivalents thereof.

In the accompanying drawing in which the same reference characters indicate the same parts in all of the views:

Figure 1 is a top view of the improved wardrobe hanger device shown attached to a wall or other support and having garment hangers mounted thereon;

Fig. 2 is a vertical sectional view thereof taken on line 2—2 of Fig. 1; and,

Fig. 3 is a detail view of a part of the device.

Referring to the drawing the numeral 5 indicates a wall of a closet or other support 35 to which the improved wardrobe hanger device 6 is connected. The device comprises a rectangular U-shaped metal strip member 7 having extensions 8 hinged to the outer ends of the side or track portions 9 of the device. 40 The hinge connections at the outer ends of the track portions 9 are provided with stop portions 11 which serve to limit the outward swing of the extensions to longitudinal alinement with their respective track portions.

The rear or securing portion 12 of the U-shaped member is provided with attaching notches or recesses 13 which are engaged by the annular recessed portions 14 of the 45 heads of the holding screws 15. The annular recesses 14 of the screws are of a size to snugly fit the recessed portions of the rear or securing portion of the device and securely and removably fasten the device to 50

the wall. The screws are provided with projecting portions 16 for convenience in turning the screws into the support.

Garment hangers 17, having hooked ends 5 18 which extend over the tracks, are adapted to be used in connection with the device.

The outer end portions of the extensible tracks are provided with upstanding stop pins 19 which are adapted to prevent the 10 garment hangers from accidentally sliding off the outer ends of the extensible tracks.

In use garments are draped over the hangers and the hangers are slidably mounted on the track portions of the device and 15 the extensible track ends are swung inwardly to closed position. In this position the hangers will be held by the extensible ends in position on the tracks. If it is now desired to remove or replace any of the garments 20 the extensible tracks may be swung outwardly and some of the hangers slid thereon to provide more space between the garments. The hanger, supporting the particular garment it is desired to remove, may 25 then be easily tilted upward and removed from the tracks and the garment removed therefrom.

From the foregoing description it will be seen that the wardrobe hanger device is of 30 simple construction and is well adapted to support a large number of garments in, comparatively, a small space.

What I claim as my invention is:

1. A wardrobe hanger device, comprising 35 a one piece rigid U-shaped member formed of a flat strip metal, the side arms of said member forming parallel track portions for supporting the opposite ends of garment hangers thereon and the rear part of said

member forming a rear attaching portion 40 provided with elongated edge recesses, and means having recessed portions which are engaged by the recessed portions of the U-shaped member for freely removably connecting the said member to a support in 45 spaced relation.

2. A wardrobe hanger device, comprising 50 a U-shaped member having parallel track portions for supporting the opposite ends of garment hangers thereon and also having a rear attaching portion provided with elongated recesses, foldable extension tracks hinged to the outer ends of the parallel track portions, and means having recessed portions which are engaged by the recessed portions of the U-shaped member for freely 55 removably connecting the said member to a support in spaced relation.

3. A wardrobe hanger device, comprising 60 a one piece rigid U-shaped member formed of flat strip metal, the side arms of said member forming parallel track portions for supporting the opposite ends of garment hangers thereon and the rear part of said member forming a rear attaching portion 65 provided with elongated edge recesses, and threaded members having annularly recessed portions which are engaged by the recessed portions of the U-shaped member for freely removably connecting the said member to a support in spaced relation.

In testimony whereof, I affix my signature, in presence of two witnesses.

GEORGE HENRY WHEARY.

Witnesses:

ANNA M. NELSON,
GEORGE BENNISH.
